TOROIDAL WINDING MACHINE

Raymond W. Tibbets, Camden, Maine, assignor to Tibbets Laboratories, Inc., Camden, Maine, a corporation of Maine

Application April 27, 1954, Serial No. 425,881

4 Claims. (Cl. 242—4)

The present invention relates to winding machines and more particularly to toroidal winding machines and to means for controlling the necessary loop in the wire during the operation cycles of coil winding.

One method of winding a coil of wire on a toroidal or ring core is to place the supply to be wound on a bobbin supported by a winding ring which travels at a constant rate about its axis through the hole of the core. In employing this method each winding or operation cycle produces a turn around the core.

Heretofore several different mechanical methods have been provided for controlling the loop but these have been limited to wires having minimum diameters of approximately two mils, it having been found that a loop of wire having a diameter smaller than two mils cannot be suitably maintained in proper relationship during the winding cycle by mechanical means without undue breakage or the necessity of greatly reducing the speed of the mechanism.

Therefore it is an object of the present invention to provide a suitable means for maintaining the loop of the wire as it passes through its winding cycle so that it does not become twisted or tangled, and particularly to maintain said loop when it is formed of fine wire. Another object is to provide a means for maintaining the loop without undue breakage, while a still further object is to provide means for maintaining the loop without the necessity of greatly reducing the speed of the winding mechanism.

According to the present invention the process comprises maintaining the wire winding mechanism of the type that produce a loop during each operation cycle, submerged in a viscous fluid, at least to the extent that the loop which is formed as a result of the operation cycles is covered or immersed with the viscous fluid. In order that the loop be so covered, the winding mechanism may be partially or totally submerged.

In another aspect the invention comprises a machine for winding wire about a toroid or ring core, in which the winding mechanism is at least partially submerged in a viscous fluid. The machine comprises a winding ring which supports a bobbin from which the wire is unwound, a ring core and a receptacle with a viscous fluid therein. The winding ring, bobbin and ring core are provided with means for their rotation in the receptacle while they are at least partially submerged in the viscous fluid, preferably to the extent that the necessary loop that is formed is submerged beneath said viscous fluid.

While some of the more salient features, characteristics and advantages of the present invention have been pointed out above, others will become apparent from the following disclosure of a preferred embodiment taken in conjunction with the accompanying drawing in which:

Fig. 1 is a side view with a portion of the fluid-tight receptacle broken away; and

Fig. 2 is a top plan view.

The toroidal winding machine of the present invention has for its principal parts a fluid-tight receptacle or cas-

2

ing 1, having enclosed therein a toroid winding mechanism comprising a winding ring 2 having a bobbin 3 therein which is freely rotatable on its axis and from which the wire is fed to ring core 5 as winding ring 2 rotates about its axis and makes its cycle through the hole of the ring core.

Winding ring 2 is supported in a horizontal plane and rotated by grooved drive rollers 7 which are mounted upon shafts 8 which pass through the packing glands 9 and through the bottom of the fluid-tight receptacle 1. Positioned beneath packing glands 9 on shafts 8 are pinions 10 which are driven by gear 12 which in turn is connected to drive shaft 13 which is connected to a suitable power source.

Ring core 5 is supported and rotated at a right angle to winding ring 2 by grooved worm wheels 16 and 17 which are suitably rotated by worm 18 mounted in supporting blocks 19 which extend between the sides of U-shaped plate 20. Pressure roller 21 and its associated lever arm 22 provide the necessary weight to hold the core 5 against the drive rollers 16 and 17. The worm 18 is rotated by grooved worm gear 23 which is in turn rotated by worm 24 mounted on shaft 25 extending through the bottom of fluid-tight receptacle 1 and packing gland 26 to a suitable power source which is preferably separate from the source driving shaft 13.

The wire 27 to be wound about the ring core 5 is on bobbin 3 and, as the drive rollers 7 cause the winding ring 2 to rotate on its cycle through the hole of said core, the wire forms a loop 27.1 which is drawn taut as the ring completes its cycle. To prevent the wire 27 from becoming tangled and broken, particularly if it be fine wire, a viscous fluid F is placed in casing 1 to the level designated by dotted line 30. When the ring core 5 is completely wound with wire 27, the lever arm 22 of pressure roller 21, which is pivotally mounted at 32 on stand 33 is raised upwardly, and wound ring core 5 is removed and a new one inserted.

Of course it is not necessary to submerge all of the above described winding mechanism since the viscous fluid need only be present in an amount sufficient to cover the loop. In addition it is obvious that in a device employing the winding ring in a horizontal position, less fluid is required to cover the mechanism. The presence of the viscous fluid is a highly efficient means of controlling the wire loop in that the drag of the wire through the viscous medium automatically maintains the loop and in addition the viscosity of the medium also tends to tension the wire during winding.

The viscous fluid employed is preferably oil so that, in addition to maintaining the loop and providing tension on the wire, it serves to lubricate the working parts within the receptacle and thereby helps to maintain their working life. It will be noted that so long as the fluid does not harm the working parts and so long as it is of such viscosity as to provide the proper drag for the loop, it is suitable for use in the present invention.

It will be noted that the ring core 5 is independently operated from the winding ring drive means. This is to permit the winding of any amount of wire on the core and so that the core may be reversed or oscillated in the event it is desirable to wind only a segment of the ring core.

The viscosity of the fluids suitable for use in the present invention have been found to have a reasonably large range. Suitable for use with soft copper wire having a diameter of 1.5 mils, which is being wound at 1000 R. P. M., is an oil having a Saybolt viscosity at 100° F. of 85 to 95 seconds. It will be obvious that for wires having larger diameters a more viscous oil is desirable in that the loop is maintained by virtue of the viscosity of the oil. Of course the speed at which the machine

operates is a contributing factor to the maintenance of the loop formation inasmuch as the greater the speed of the winding ring the more resistance is experienced by the loop with a given viscosity of oil. Therefore both of the factors must be given consideration in determining the viscosity.

Of course the term "fine wire" is relative and for practical purposes of this invention includes wire having a diameter up to two mils and more, which diameters, particularly in soft wire, have not heretofore been as successfully wound as when the present invention is employed. It should be noted that the spirit of the invention is applicable to any rapid winding operation wherein a necessary loop is formed and the maintenance of the loop and the avoidance of tangling and breakage of the wire is a problem regardless of the diameter of the wire.

It will be understood that the above disclosure is for the purpose of illustration only and that the invention must include all modifications and equivalents which fall within the scope of the appended claims.

I claim:

1. A machine for winding wire about a core comprising a container, liquid in the container up to a predetermined level therein, a bobbin ring adapted to carry the wire and having a portion disposed in the liquid below said level, and means for moving the bobbin ring in an orbital path for repeatedly throwing loops of said wire around the core and then drawing the loops taut, said loops being submerged in the liquid, whereby the liquid prevents the loops of wire from twisting or tangling while being drawn around the core.

2. A machine for winding wire about a ring core comprising a container, liquid in the container up to a predetermined level therein, means for rotating the core about its axis in the liquid below said level, a bobbin ring adapted to carry the wire and extending through the core in a plane containing said axis, and means for rotating the bobbin ring about its axis while submerged repeatedly to throw loops of said wire around the ring core and then draw the loops taut, said loops being submerged in the liquid, whereby the liquid prevents the

loops of wire from twisting or tangling while being drawn around the core.

3. A machine for winding wire about a core comprising a container, liquid in the container up to a predetermined level therein, a bobbin ring adapted to carry the wire and having a portion disposed horizontally in the liquid below said level, means for supporting a core within said ring, and means for rotating the bobbin ring about its axis while said portion is submerged repeatedly to throw loops of said wire around the ring core and then draw the loops taut, said loops being submerged in the liquid, whereby the liquid prevents the loops of wire from twisting or tangling while being drawn around the core.

4. A machine for winding wire about a ring core comprising a container, liquid in the container up to a predetermined level therein, means for rotating the core about a horizontal axis extending through the core coaxially in the liquid below said level, a bobbin ring adapted to carry the wire and extending through the core in a horizontal plane containing said axis, and means for rotating the bobbin ring about its axis while submerged repeatedly to throw loops of said wire around the ring core and then draw the loops taut, said loops being submerged in the liquid, whereby the liquid prevents the loops of wire from twisting or tangling while being drawn around the core.
